CLAIM

The ornamental design for a connector, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a connector showing the claimed design.

The dot-dash broken lines in the FIGURE and the area within the dot-dash broken lines show portions of the connector that form no part of the claimed design.
